UNITED STATES PATENT OFFICE.

GEORGE W. T. ANDERSON, OF JACKSONBURG, WEST VIRGINIA.

RAIL-JOINT.

1,088,177.

Specification of Letters Patent. Patented Dec. 30, 1913.

Application filed September 11, 1912. Serial No. 719,789.

To all whom it may concern:

Be it known that I, GEORGE W. T. ANDERSON, a citizen of the United States, residing at Jacksonburg, in the county of Wetzel 5 and State of West Virginia, have invented new and useful Improvements in Rail Joints, of which the following is a specification.

An object of the invention is to provide 10 a rail joint for securing rail ends in position on rail ties.

The invention embodies, among other features, a bed plate adapted to be supported on a cross tie and provided with an integral 15 depending base extending into a groove in the tie, a side plate formed with the said bed plate and bent to engage the webs of rail ends mounted on the said bed plate, and a second side plate mounted to slide and to 20 turn on the bed plate and movable to engage the webs of the rail ends, with the rail ends interposed between the rigid side plate and the movable side plate, suitable bolts being arranged to extend through the webs of the 25 rail ends and through the side plates to secure the rail ends in position on the bed plate.

In the further disclosure of the invention reference is to be had to the accompanying 30 drawings, constituting a part of this specification, in which similar characters of reference denote corresponding parts in all the views, and in which:

Figure 1 is a side elevation of the rail joint; Fig. 2 is a vertical transverse sectional view taken on the line 2—2 in Fig. 1; Fig. 3 is a vertical longitudinal sectional view; and Fig. 4 is a perspective view of the movable side plate.

Referring more particularly to the views, use is made of a bed plate 10 having formed integrally therewith and depending from the under side thereof a curved rib 11 adapted to repose in a groove 12 formed in 45 a tie 13. The rib 11 does not continue the entire length of the plate 10, but is omitted for a suitable distance from its ends, and is of its greatest depth at its central portion which is received within the said tie 13. The flat underside of the base, at its ends 50 rests upon ties disposed opposite the central tie 13. The rib 11 is of a width corresponding to or slightly less than that of the base flange of the rail ends 15 which are 55 adapted to be disposed upon the plate directly over the said rib. The plate 10 has

its opposite ends bent to provide inwardly extending portions 10^a and 10^b which overlie the plate proper, and owing to the natural resiliency of the metal, the said portions 10^a and 10^b may have their inner or edge portions slightly spaced away from the base proper, as will be readily understood. The portion 10^a has integrally formed therewith a side plate 14, which comprises an angular member and a vertical member, both of which being so shaped as to engage within the fishing spaces to the sides of the rail upon which they are positioned. The overlying portion 10^b has its end rounded upwardly to provide a longitudinally extending lip 17, and the lower and outer wall of said lip is disposed a suitable distance above the body of the overlapping portion 10, as disclosed in Fig. 2 of the drawings.

The numeral 18 designates an angular fish plate which has its longitudinal edge enlarged and grooved upon its upper face to provide a longitudinally extending lip 19 which is adapted to be received within the lip 17 of the member 10^b. If desired, the said longitudinal edge of the fish plate 18 may be bent to provide its edge of a substantially cross sectionally U-shaped formation, and the engaging lips 17 and 19 provide a hinge connection between the member 10^b and the plate 18.

It is not absolutely essential that the ends of the bed plate overlying members 10 and 10^b, spread away from the said plate, but it will be noted that both of said members provide substantially spring members, owing to their natural resiliency. Such a resiliency permits of the insertion of the lip 19 within the lip 17 without necessitating the sliding movement of the fish plate 18, and also permits of a free insertion of the rails against the walls of the side member 14, before the said plate 18 is applied. The vertical members of the portion 14 and the fish plate 18 are provided with openings 20 which register with similar openings in the webs of the rails. Passing through the alining openings are bolts 21 which are provided with the usual securing nuts. The outer longitudinal edges of the joint member have depressions or slots 22 which are adapted to receive spikes 24, the said spikes entering the ties and having their heads pressing against the upper faces of the portions 10^a and 10^b to sustain the underfaces of said portions tightly against the upper face of

the bed plate proper, and as a consequence, the lip 17 is forced into tight frictional engagement with the lip 19 which also tends to force the plate 18 into tight frictional engagement with the rails with which it engages, while the angular portion 14 is likewise forced into light frictional engagement with the opposite sides of the rails.

From the above description, taken in connection with the accompanying drawings, the simplicity of the device as well as the advantages thereof will, it is thought, be perfectly apparent to those skilled in the art to which such inventions appertain without further detailed description.

Having thus described the invention, what I claim as new is:

In a rail joint, a bed plate having its underside formed with a centrally arranged longitudinal extending curved rib, and two rails adapted to rest upon the plate directly over its rib, the said plate having its ends bent to provide inwardly extending members which overlie the bed plate proper, one of said overlying portions having a side which constitutes an inwardly extending inclined portion and a vertically straight portion, whereby the said side engages within

the fishing spaces of the rails, the second overlying portion having its end curved to provide a longitudinally extending lip, the edge of which being arranged above the bed plate proper, and the said lip terminating a slight distance away from the longitudinal edges of the base flanges of the rails, an angular fish plate having its longitudinal edge substantially U-shaped to provide a lip that is adapted to co-act with the first mentioned lip, the vertical plates of the fish plate and of the side member having openings which register with openings in the webs of the rails, securing elements passing through the openings, the outer longitudinal edges of the bed plate and its overlying portions having notches, and spikes adapted to pass through the notches into the supporting ties and to have their heads contact with the overlying portions of the bed plate.

In testimony whereof I affix my signature in presence of two witnesses.

GEORGE W. T. ANDERSON.
